UNITED STATES PATENT OFFICE.

FRANK L. CONE, OF WINDSOR, VERMONT.

STOCK PUSHER.

Application filed February 3, 1923. Serial No. 616,690.

To all whom it may concern:

Be it known that I, FRANK L. CONE, a citizen of the United States, residing at Windsor, in the county of Windsor and State of Vermont, have invented new and useful Improvements in Stock Pushers (Case B), of which the following is a specification.

This invention relates to stock pushers such as are used to engage and feed forward the stock in automatic lathes and screw machines. For this purpose it has been proposed to use a plurality of stock-clamping elements urged against the stock by spring rings sprung therearound, the whole being enclosed within a sleeve provided with internal shoulders positioned to hold these elements from motion longitudinally within the sleeve. This construction, however, has among others the disadvantage that the size capacity of the machine is considerably reduced since the internal diameter of the series of elements is materially smaller than the internal diameter of the sleeve.

According to the present invention the stock-engaging elements have a flexible interlocking connection with the sleeve at one end only by which they can be made of increased diameter since the sleeve is not required to house these elements and their springs.

For a more complete understanding of this invention, reference may be had to the accompanying drawings in which—

Figure 1 is a side elevation of the device.

Figure 2 is a forward end elevation.

Figure 3 is a longitudinal section on line 3—3 of Figure 2.

Figure 4 is a cross section on line 4—4 of Figure 3.

Figure 5 is a perspective of one of the stock-engaging elements.

Referring to these figures, 1 indicates a sleeve having a reduced threaded extremity 2 for attachment to the usual mechanism for imparting movement to the device. The other end of the sleeve 1 has an annular recess 3 of larger diameter than the normal bore of the sleeve which terminates at its end opposite the portion 2 with an annular inwardly directed rib or flange 4. The other extremity of the recess 3 is formed by means of a shoulder 5.

The stock-engaging elements are shown at 6 and comprise segmental members, each of which has one end formed with a portion of larger diameter as shown at which

when the parts are arranged in series forms an annular shoulder which fits loosely within the recess 3 of the sleeve 1. Outwardly of the portion 4 each of these segments has an extension 8, the extensions of all the elements 6 together forming an annular rib or shoulder and the opposite ends of these members have extensions 9 which together form an annular rib at the end of the series. Between the ribs 8 and 9 are adapted to be positioned one or more split spring rings 10. As shown the segmental sections are formed to rock on each other, for this purpose each being provided with a pin or fulcrum member 11 projecting from one side closely adjacent the portion 8. The springs 10 then act to force the outward ends of the element 6 toward each other, rocking the members about their fulcrum points 11, this action serving also to separate the inner ends of the sections to retain the portion 7 within the recess 3 and to open the inner ends of the sections to their maximum extent to receive stock presented thereto through the opposite end of the sleeve. The elements 6 thus interfit and interlock flexibly with the sleeve. The inner end of the bore of the members 6 may be flared as shown at 16 to conform to the interior diameter of the sleeve so that stock may be readily guided therebetween, the stock when in position, retaining the elements 6 out of contact with each other. In order that they may be assembled and disassembled with relation to the sleeve 1, the adjacent sides of the portion 6 are cut away as shown at 12 so that the outer ends of the segments 6 are permitted to be separated, these segments rocking about their pivots 11 to retract the portions 7 from the recess 3 so as to permit them to be withdrawn endwise from the sleeve 1.

A dowel pin 15 is shown as extending inwardly from the sleeve into the recess 3 and when the elements 6 are in position this dowel projects between an adjacent pair within the cutouts 12 and so retains them from rotation relative to the sleeve. As shown three such elements 6 are provided though more might be provided if desired and when three are used, the one not engaged by the dowel is free to be rocked inwardly to be released from the sleeve, whereupon the pair in contact with this dowel may be separated therefrom and removed.

It will be seen from this description that the stock-engaging elements are flexibly

united to the sleeve at one end only and otherwise are not housed by the sleeve which therefore is not required to be of sufficient internal diameter to pass about the stock-engaging elements and their actuating springs so that the internal diameters of the sleeve and elements may be more nearly equal than could otherwise be the case.

Having thus described an embodiment of this invention it should be evident that many modifications and changes might be made therein without departing from its spirit or scope as defined by the appended claims.

15 I claim:

1. A device of the class described comprising a sleeve, a plurality of stock-engaging elements extending outwardly of said sleeve and formed at one end to interfit one end of said sleeve and means for urging such elements inwardly to grip stock extending therebetween and through said sleeve.

2. A device of the class described comprising a sleeve, a series of stock-engaging elements longitudinally rockable on each other and springs surrounding said series and urging said elements into stock-clamping position, one end of said series of elements and one end of said sleeve being 30 formed to interlock.

3. A device of the class described comprising a sleeve, a series of stock-engaging elements rockable on each other, springs surrounding said series adjacent said end and urging said elements into stock-clamping position, the other ends of said elements and one end of said sleeve being formed to interlock, and means for preventing relative rotation of said elements and sleeve about 40 the axis of said sleeve.

4. A device of the class described comprising a sleeve having at one end an internal enlargement defined at the end of the sleeve by an internal annular rib, a plurality of segmental stock-engaging elements each having a projection at one end forming when said elements are assembled an external annular rib fitting into said enlargement and preventing disengagement of said elements from said sleeve, the faces of said elements adjacent each other being cut away at their inner ends whereby their outer ends may be separated to withdraw their inner ends from interlocking engagement with 50 said sleeve, and means for urging said outer ends together into clamping relation to stock extending therebetween and through said sleeve.

5. A device of the class described comprising a sleeve having at one end an internal enlargement defined at the end of the sleeve by an internal annular rib, a plurality of segmental stock-engaging elements each having a projection at one end forming when said elements are assembled an exter-

nal annular rib fitting into said enlargement and preventing disengagement of said elements from said sleeve, the faces of said elements adjacent each other being cut away at their inner ends whereby their outer ends may be separated to withdraw their inner ends from interlocking engagement with said sleeve, each of said elements having an external projection adjacent its outer end and an external projection adjacent the end of said sleeve these projections defining annular ribs when said elements are assembled, and one or more spring rings engaging about said elements between said ribs for holding said outer ends closed so against stock therebetween and said inner ends interlocked with said sleeve.

6. A device of the class described comprising a sleeve having at one end an internal enlargement defined at the end of the sleeve by an internal annular rib, a plurality of segmental stock-engaging elements each having a projection at one end forming when said elements are assembled an external annular rib fitting into said enlargement and preventing disengagement of said elements from said sleeve, the faces of said elements adjacent each other being cut away at their inner ends whereby their outer ends may be separated to withdraw their inner ends from interlocking engagement with said sleeve, each of said elements having an external projection adjacent its outer end and an external projection adjacent the end of said sleeve these projections defining annular ribs when said elements are assembled, one or more spring rings engaging about said elements between said ribs for holding said outer ends closed against stock therebetween and said inner ends interlocked with said sleeve.

7. A device of the class described comprising a sleeve having at one end an internal enlargement defined at the end of the sleeve by an internal annular rib, a plurality of segmental stock-engaging elements each having a projection at one end forming when said elements are assembled an external annular rib fitting into said enlargement and preventing disengagement of said elements from said sleeve, the faces of said elements adjacent each other being cut away at their inner ends whereby their outer ends may be separated to withdraw their inner ends from interlocking engagement with said sleeve, each of said elements having an external projection adjacent its outer end and an external projection adjacent the end of said sleeve these projections defining annular ribs when said elements are assembled, one or more spring rings engaging about said elements between said ribs for holding said outer ends closed against stock therebetween and said inner ends interlocked with

said sleeve, and a pin fixed to said sleeve and engaging one or more of said elements to prevent relative rotation between said elements and sleeve.

- 5 8. A device of the class described comprising a sleeve having at one end an internal enlargement defined at the end of the sleeve by an internal annular rib, a plurality of segmental stock-engaging elements each having 10 a projection at one end forming when said elements are assembled an external annular rib fitting into said enlargement and preventing disengagement of said elements from said sleeve, the faces of said elements 15 adjacent each other being cut away at their inner ends whereby their outer ends may be separated to withdraw their inner ends from interlocking engagement with said sleeve, each of said elements having an external 20 projection adjacent its outer end and an external projection adjacent the end of said sleeve these projections defining annular ribs

when said elements are assembled, one or more spring rings engaging about said elements between said ribs for holding said 25 outer ends closed against stock therebetween and said inner ends interlocked with said sleeve, and a pin fixed to said sleeve and engaging between a pair of adjacent elements to prevent relative rotation between said ele- 30 ments and sleeve.

9. A device of the class described comprising a series of stock-engaging elements, a holder for said elements and spring means for retaining said elements assembled with 35 relation to said holder.

10. A device of the class described comprising a sleeve, a series of stock-engaging elements, and springs for retaining said elements assembled with said sleeve. 40

In testimony whereof I have affixed my signature.

FRANK L. CONE.
